DEVICE FOR DETERMINING THE CONDITION OF A WELL BORE FROM AN ETCHED ACID BOTTLE

Ferdinand J. Spang, Butler, Pa.

Application January 24, 1942, Serial No. 428,068

5 Claims. (Cl. 235—69)

This invention relates to the acid bottle method of testing well bores or shafts for the purpose of determining their angular position. This method is old in the art and is usually carried out as follows:

A common chemical bottle partially filled with a dilute aqueous solution of hydrofluoric acid is so secured within a tube that it is axially aligned therewith. This tube is of such length and diameter that when it is lowered into the well bore hole, it will be in axial alignment with such bore hole, thus insuring axial alignment of acid bottle and bore hole.

The tube with the acid bottle secured therein is lowered to a predetermined depth within the well bore hole and is kept at such depth for a time which is sufficient to allow the fumes from the acid solution within the bottle to attack and etch the exposed inner surface of the bottle above the acid solution level, thus forming on the inner surface of the bottle a well defined line of demarcation at such level. The tube with the acid bottle therein is then withdrawn from the well bore hole, and the acid bottle is removed from the tube and rinsed with water in order to terminate the etching action.

Heretofore, it has been customary to determine the angular position of the demarcation line within the etched bottle by means of bevel protractors or the like, and then, by means of computations to determine the angular position of the well bore hole.

An object of this invention is to produce a device or instrument by means of which the angularity of the well bore hole, or in other words its departure from the vertical, can be readily and quickly determined from the demarcation line which has been produced in an acid bottle in the usual manner as above outlined.

Another object is to produce a device or instrument by means of which the ordinary factors relating to a well bore hole condition can be quickly and accurately computed and determined from the demarcation line once such line has been formed in the usual manner on the inner surface of an acid bottle.

These and other objects which will be apparent to those skilled in this particular art, I attain by means of the device described in the specification and illustrated in the drawing accompanying and forming part of this application.

In the drawing:

Figure 1 is a top plan view of a device or instrument embodying this invention with an etched acid bottle in place therein;

Fig. 2 is a longitudinal sectional view of the device of Fig. 1; and

Fig. 3 is a transverse view taken on line III—III of Fig. 2.

5 In a general way, the device or instrument of this invention comprises an acid bottle holder, a pair of relatively movable slides associated with said holder, means for so supporting said slides that their relative sliding movement is limited 10 to parallel paths which parallel the longitudinal axis of an acid bottle located in position within said holder, and scales on said slides which compute and determine the ordinary necessary factors relating to the condition of a well bore hole 15 from the demarcation line in an acid bottle that has been etched within such bore hole in the usual manner.

In the device or instrument chosen for illustrating this invention, the acid bottle holder is 20 formed in the nature of a case or housing 4 which is generally cylindrical and is open at its forward end 5 to receive within the bottle compartment thereof of a bottle 6. The bottom or rear end of the compartment is partially closed by an annular 25 flange 7 which forms a stop and against which the bottom of the bottle abuts when in position within its compartment.

The case or housing is arranged to lie in a horizontal position when being used and is provided 30 with support feet 8. The top of the case or housing is provided with a central slot 9 which, extending from end flange 7 to the forward end of the bottle compartment, extends an equal distance on opposite sides of the longitudinal axis 35 of the case.

The case on opposite sides of the slot 9 is provided with dovetail slideways 10 and 11 which extend throughout the length of the housing and parallel the longitudinal center line of the case or housing and that of bottle 6 when in position within its compartment.

40 A slide 12 is dovetailed to slideway 10 and a slide 13 is dovetailed to slideway 11. These slides meet at the longitudinal median line of slot 9, and are capable of being independently moved along their respective slideways.

45 Slide 12 is provided with two scales arranged end to end. The forward scale 14 or that nearest its pointed end 15 is calibrated to give the corrected vertical depth of the bore hole in feet per hundred feet of lineal bore hole measurement. Rear scale 16 is calibrated to give the difference in inches between the points of maximum and minimum height of the demarcation line in the acid bottle.

Slide 13 is also provided with two scales which are numbered 17 and 18. The forward scale, or scale 17 which is nearest the pointed end 19 of slide 15 is calibrated to give the distance in feet from the center of the well bore hole where the etching occurred in the acid bottle to a vertical line which passes through the center of the well bore hole at the ground level. Scale 18 is calibrated to give the degree of angularity to the vertical of the plane within which the demarcation line in the acid bottle is located. The demarcation line is numbered 20.

Slide 13 is provided with an arrow 21, which, when the slides are properly adjusted with relation to the demarcation line, designates the point on scale 14 which sets forth the corrected vertical depth in feet per hundred feet of bore bore hole measurement. Slide 13 also has an arrow 22, which, when the slides are properly adjusted with relation to the demarcation line, designates the point on scale 16 which sets forth the difference in inches between the maximum and minimum (high and low) points in the demarcation line.

Slide 12 is provided with an arrow 23, and this arrow, when the slides are properly adjusted with relation to the demarcation line, designates the point on scale 17 which sets forth the distance from the center of the well bore hole where the etching in the acid bottle occurred, to a vertical line which passes through the center of the well bore hole at the ground level. Slide 12 is also provided with an arrow 24, which, when the slides are adjusted to proper position with relation to the demarcation line, designate the point in scale 18 which gives the degree of angularity to the vertical of the plane of the demarcation line.

Leaf springs 25 located within the bottle compartment of the case or housing below the longitudinal center line of the acid bottle when in position yieldingly hold the bottle in contact with the under longitudinal edges of slot 9 so that the major axis or longitudinal center line of the bottle is parallel to the longitudinal center line of slot 9.

These springs overlie cut-out portions 26 of the case or housing, and the rear end of each spring is preferably connected by mold metal 27 to the adjacent end wall of the cut-out portion 26. The forward end 28 of each spring projects beyond the opposite end wall of its slot 26 and is turned outwardly toward the case or housing in order to permit the bottle to be readily slid into position against stop flange 7. Springs 25 not only serve to hold the bottle in contact with the under longitudinal edges of slot 9, but frictionally hold the bottle in place. They also frictionally resist rotation of the bottle when in place.

Each slide adjacent its forward end is provided with a through hole 29. Annular flange 7 in line with each slide is provided with a pocket 30 and a pin 31 located within each said pocket, and backed by a spring 32, bears against the underside of the slide and thus frictionally resists sliding movement thereof. As the slides are moved rearwardly until holes 29 register with pins 31, said pins, by means of their backing springs 32 are forced outwardly and into said holes, thus locking the slides against further rearward movement. It will be obvious that in order to release the slides, so that they can be moved forward, it is only necessary to manually depress pins 31 and keep them depressed until the

slides are moved to a position where holes 29 are out of register with said pins.

In using the device or instrument of this invention, a bottle which has been etched in the usual or customary manner as above outlined, is inserted bottom end first, into the bottle compartment of the device, so that its base or bottom bears tightly against flange 7.

With the bottle thus positioned, the slides are moved to the rear until their pointed ends are below the lowest point of the demarcation line.

The bottle is then rotated until the lowest point of the demarcation line is midway of slot 9. Slide 12 is then moved toward the open end of the case until its point 15 is in line with the lowest point of said demarcation line. Spring pressed pin 31 which bears against the underside of slide 12 frictionally holds said slide in adjusted position.

The bottle is then rotated 180° about its axis 20 or until the uppermost point of the demarcation line is midway of slot 9. The right-hand slide 13 is then moved up until its point 19 is in line with said highest point. Slide 13 is frictionally held in adjusted position by its spring pressed pin 31.

With the slides thus adjusted, four computations may be instantly read. Arrow 21 points to the place on scale 14 which shows the corrected vertical depth of the well hole in feet per hundred feet of lineal well bore measurement. Arrow 22 points to the place on scale 16 which shows the difference between the upper and lower points in the demarcation line. Arrow 23 points to the place on scale 17 which shows the distance measured in feet from the center of the well bore at the point where etching of the bottle occurred to the nearest imaginary vertical line which is in alignment with the location of the well bore at the ground level. Arrow 24 points to the place on scale 18 which shows the degree of angularity of the bore hole with respect to said imaginary vertical line.

It will be apparent that the slides may be set or adjusted to low and high points of a demarcation line in an etched bottle which has been measured by some other means. For example, these measurements may be taken at some distant point and telegraphed or otherwise transmitted to someone having one of these devices, who can then quickly determine the condition of the well bore as it relates to said imaginary vertical line.

It will be apparent that by use of this device, the computations or readings of the four calibrated scales can be rapidly arrived at, so that 55 drilling operations or other work need only be delayed long enough to obtain the etched demarcation line.

These readings may then be used to plot the condition of the well bore in such a way as to 60 acquaint the geologist, or others interested therein of its location as regards the objective of the well drilling. This is particularly valuable where geophysical soundings have been made to predetermine the expected locations of productive horizons within the well bore. For instance, a petroleum producing zone may be located at a certain depth from the surface and it may slope from the horizontal at some degree of angularity. If the well bore becomes crooked, or veers from 65 the vertical, thus shortening the vertical distance, measurements made by depth measuring lines become meaningless. However, these measurements in connection with the readings derived from the scales of this device can be converted into other measurements which will

indicate the point at which the drilling tools may enter the formation. If the formation is one of some horizontal angularity it may be reached at a shorter or at a greater depth, depending upon the position at which it is struck, so that by means of these measurements, and the plat of the formation, a fairly accurate determination of the penetration point can be made.

It is of course, recognized that numerous methods of surveying well bore holes are now in use. Most of these are quite expensive, because of the elaborate equipment that is needed.

Aside from this, the time lost during the use of these methods makes their use costly, whereas the device of this invention may be used daily, and well bore corrections made when needed as drilling of the bore hole progresses.

Having thus described my invention, what I claim as new and desire to secure by Letters Patent is:

1. In a device for obtaining unknown factors such as the corrected vertical depth of a well bore hole in feet per hundred feet of lineal well bore measurement and the distance horizontally from the center of such bore hole to a vertical line passing through the center of the bore hole at the ground level, from, the demarcation line in an acid bottle that has been etched within such bore hole in the usual way; a pair of juxtaposed relatively slidable members, a scale on each such member, one graduated for such corrected vertical depth, with the other graduated for such distance, and a pointer on each such member so placed as to co-operate with the scale on the other member in designating the point on such scale which sets forth such unknown factor; the construction and arrangement being such that when such members are relatively slid until the lowest point of the horizontal distance scale is advanced beyond the lowest point of the corrected vertical depth scale a distance equal to the known distance between the high and low points in the demarcation line of an acid bottle having an internal diameter properly correlated to said scales, said pointers will be brought into matched line position with such unknown factors.

2. In a device for obtaining unknown factors such as the corrected vertical depth of a well bore hole in feet per hundred feet of lineal well bore measurement and the distance horizontally from the center of such bore hole to a vertical line passing through the center of the bore hole at the ground level, from the demarcation line in an acid bottle that has been etched within such bore hole in the usual way; a pair of juxtaposed relatively slidable members, two scales on one such member arranged in end to end relation with one graduated for such corrected vertical depth and the other graduated for the difference in height between the minimum and maximum points in such demarcation line, a scale on the other member graduated for such horizontal distance, two pointers on the second mentioned scale so placed as to co-operate with the scales on the first mentioned member and one pointer on the first mentioned member so placed as to co-operate with the scale on the second mentioned member; the construction and arrangement being such that when such members are relatively slid until the pointer for the scale showing the difference in height between the maximum and minimum points in the demarcation line is brought into matched line position with the known distance between such points,

the other pointers will be brought into matched line position with the unknown factors.

3. In a device for obtaining unknown factors such as the corrected vertical depth of a well bore hole in feet per hundred feet of lineal well bore measurement and the distance horizontally from such bore hole to a vertical line passing through the center of the bore hole at the ground level, from the demarcation line in an acid bottle that has been etched within such bore hole in the usual way; a pair of juxtaposed relatively slidable members, a scale on one such member graduated for such corrected vertical depth, two scales on the other member arranged in end to end relation with one such scale graduated for such distance and the other graduated for the angle of etching in degrees in the acid bottle, two pointers on the first mentioned member so placed as to co-operate with the scales on the second mentioned member and one pointer on the second mentioned member so placed as to co-operate with the scale on the first mentioned member; the construction and arrangement being such that when such members are relatively slid until the pointer for the scale showing the angle of etching is brought into matched line position with the known angle of etching the other pointers will be brought into matched line position with the two unknown factors.
4. In a device for obtaining unknown factors such as the corrected vertical depth of the well bore hole in feet per hundred feet of lineal well bore measurement and a distance horizontally from the center of such bore hole to a vertical line passing through the center of the bore hole at ground level, from the demarcation line of an acid bottle that has been etched in the well bore hole in the usual way, a pair of juxtaposed relatively slidable members, two scales on each such member arranged in end to end relation with one scale on one member graduated for such corrected vertical depth, with the other graduated for the difference in inches between the high and low points in such demarcation line, one of the scales on the other member being graduated for such horizontal distance, with the other scale on such member graduated to the angularity of such demarcation line, a pointer on each such member so placed as to co-operate with the scale on the other member which sets forth an unknown factor; the construction and arrangement being such that when such members are relatively slid until the pointer co-operating with the scale showing the difference in height between the maximum and minimum points in the demarcation line is brought into matched line position with the known distance between such points, or the pointer co-operating with the scale showing the angle of etching is brought into matched line position with the known angle of etching, the other pointers will be brought into matched position with the two unknown factors.
5. In a device for obtaining two unknown factors of a well bore hole from the demarcation line in an acid bottle that has been etched within such bore hole in the usual way, a member having thereon two scales arranged in end to end relation and each comprising lines and numerals, a second member having thereon two scales each comprising lines and numerals, means for mounting said members contiguously whereby one is slidable with relation to the other, pointers on each such member for co-operating with the scales on the other member, said scales being calibrated to certain factors such as angle of in-

clination of the demarcation line in degrees, horizontal distance of etching point from a vertical line passing through the center of the bore hole at the ground level, corrected vertical depth in feet per hundred feet of lineal well bore hole measurement and the difference in inches between the maximum and minimum points in the demarcation line of a bottle having an internal diameter properly correlated with said scales; the construction and arrangement being such that when such members are relatively slid until the

pointer co-operating with the scale showing the difference in height between the maximum and minimum points in the demarcation line is brought into matched line position with the known distance between such points, or the pointer co-operating with the scale showing the angle of etching is brought into matched line position with the known angle of etching, the other with the two unknown factors of the well bore hole.

FERDINAND J. SPANG.
